CLAIM

The ornamental design for a handle for kitchen tools and gadgets, as shown and described.

DESCRIPTION

FIG. 1 is a front elevational view of a handle for kitchen tools and gadgets, showing our new design;

FIG. 2 is a left side elevational view thereof;

FIG. 3 is a rear elevational view thereof;

FIG. 4 is a right side elevational view thereof;

FIG. 5 is a left end plan view thereof; and,

FIG. 6 is a right end plan view thereof.

The broken line showings of a spaghetti fork in the figures are for illustrative purposes only and form no part of the claimed design.
